W. H. Tracy, Attorney.

UNITED STATES PATENT OFFICE.

ELMER H. JOHNSON, OF NORTH BENNINGTON, VERMONT.

PUZZLE.

1,283,201.

Specification of Letters Patent. Patented Oct. 29, 1918.

Application filed December 10, 1917. Serial No. 206,491.

To all whom it may concern:

Be it known that I, ELMER H. JOHNSON, a citizen of the United States, residing at North Bennington, in the county of Bennington and State of Vermont, have invented certain new and useful Improvements in Puzzles, of which the following is a specification.

This invention relates to puzzle or game devices and has as its object to provide a device of this class which will prove highly interesting and which will require the exercise of judgment as to distances, thus proving instructive as well as interesting.

Another object of the invention is to provide a puzzle which may be manufactured at a relatively low cost, which will occupy but little space, and which in various other ways will be particularly desirable from a commercial point of view.

Another object of the invention is to provide a device of the class mentioned which will possess an educational value in a sense that it will enable one to become more or less familiar with geographical subjects.

In the accompanying drawings:

Figure 1 is a plan view of the base of the device embodying the present invention;

Fig. 2 is a vertical sectional view on the line 2--2 of Fig. 1;

Fig. 3 is a view in side elevation of the member which is to be moved over the base in the solving of the puzzle or playing of the game;

Fig. 4 is a view partly in elevation and partly in section illustrating a slight modification of the invention.

The base of the device embodying the present invention is preferably in the nature of a flat board 1 which may be of wood or any other suitable material, and upon the upper side of which is secured in any suitable manner a facing sheet 2. It will be understood, however, that the upper face of the board 1 may in itself comprise the playing surface of the base, in which event the sheet 2 may be dispensed with, and that the said board 1 may be made either of wood, or of metal or any other suitable material. In any event the playing surface of the base has depicted thereon at one side, a portion of the map of the United States, as indicated by the numeral 3, and at the other side a greater or less portion of the maps of two of the allied nations, namely, England and France, as indicated by the numeral 4, the

intermediate portion of the surface of the base representing, of course the Atlantic Ocean. At this point it may be stated that the member which is to be moved over the surface of the base is in the nature of a miniature ship and the object in view in solving the puzzle is to move this ship from a starting point at the coast line of the United States, to an objective point, which in the present instance is the point representing Bordeaux, France, certain intermediate points representing submarines and being located between the starting and objective points and to be avoided by the ship in its passage from the starting point to the objective point. There may be one or any desired number of starting points indicated upon the face of the base and in the present instance one of these points, indicated by the numeral 5, has approximately the location of New York city upon the map of the United States, and another starting point, indicated by the numeral 6, may be located, for example, at a point in the Atlantic coast line of Florida. The objective point indicated in general by the numeral 7, is suitably designated upon the surface of the base as Bordeaux. The portions of the map representing the United States and the allied nations above referred to may be more or less complete in the designation of cities, ports, etc. At the starting point 5 the base is formed with a socket 8, and a similar socket 9 is formed at the starting point 6. There is also formed in the base a socket 10 which is represented as located at the objective point 7. The base is also formed between the starting and objective points with a plurality of variously spaced sockets 11, and some of these sockets are especially designated to indicate the positions of submarines which must be avoided by the movable member of the device representing the ship. Thus, for example, the particular sockets just mentioned may be indicated by the abbreviation Sub as at 12, or some other suitable indicating device or means may be employed. The sockets 8, 9, 10 and 11 may be formed to extend completely through the base as shown in Fig. 1, or only partly through the base, or in a less expensive embodiment of the invention the various starting, objective and intermediate points might be merely designated by dots, printed or otherwise depicted upon the playing surface of the base.

The member which is movable across the board or base is as above stated in the nature of a miniature ship comprising a body 13 which in that form of the invention shown in Fig. 3 of the drawings is provided upon its under side with downwardly projecting studs 14 which are definitely spaced with relation to each other and are relatively immovable being integral with the body 13. By comparison of Figs. 1 and 3 it will be observed that while the sockets in the surface of the base are variously spaced with relation to one another, each socket is spaced from one or more adjacent sockets a distance equal to the distance between the studs 14 upon the body 13. Thus when the miniature ship 13 is so disposed upon the board that one of its studs will seat in any one of the sockets, one or several other sockets will be located on the circle which would be described by the other one of the studs 14 in swiveling the miniature ship about the first-mentioned stud as a pivot. One or several other sockets may be so spaced from the first mentioned socket as to be located within the circle and the greater number of the other sockets will be located exteriorly of the circle, but the studs 14 can only be simultaneously engaged in the sockets which are spaced apart a distance equal to the distance between the studs. Therefore, in solving the puzzle the miniature ship will first be placed in position upon the playing surface of the base with one of its studs engaging in the socket 8 or the socket 9 either as desired, and the ship will then be swiveled about this stud as a center until its other stud engages in a related socket, by which is meant one of the sockets 11 spaced from the starting point a distance equal to the distance between the studs 14. The ship may then be swiveled upon its last-mentioned stud until its first-mentioned stud engages in one of the sockets 11 related to the socket in which the said last-mentioned stud is seated, and this swiveling of the ship is to be continued until the ship has been brought to position with the engagement of either of its studs 14 in the socket 10 at the objective point 7, with the exception that the ship must not be swiveled by engaging either of its studs in any of the sockets indicating the positions of submarines, although these particular sockets are each related to one or more other sockets in which the studs 14 may properly engage. It will be understood, of course, that in that simplified form of the invention above referred to in which the surface of the board is provided with dots to indicate the intermediate points instead of with sockets, the studs 14 are to be merely brought into registration with the dots and the miniature ship carefully swiveled upon the studs. How-

ever, it is, of course, preferable to make use of the sockets as in this manner the swiveling points for the ship are positively determined and maintained during the back and forth turning of the ship in working it across the surface of the base. 65

In that form of the invention shown in Fig. 4 of the drawings, the base may be provided with upstanding studs 15 which take the place of the sockets 8, 9, 10 and 11, and the body of the ship may be formed with spaced sockets 16 to receive said studs 15 and 75 corresponding to the studs 14 in the previously described form of the invention.

In the claims I will make reference to idle sockets and idle points and by this expression I refer to the sockets or points which 80 represent the location of submarines.

Having thus described the invention, what is claimed as new is:

1. A puzzle comprising a base having geographical outlines on its surface along opposite edges with objectives located on said outlines, the surface of the base being further provided with a plurality of variously spaced intermediate points, some of said intermediate points being idle and having 85 danger indications adjacent thereto, and a manually manipulable member having definitely spaced points to be engaged with an objective and successively and selectively engaged with intermediate points whereby the 90 member will be moved across the base to engage a second objective, each intermediate point being spaced from one or more adjacent points a distance equal to the distance 95 between the points on the member. 100

2. A puzzle comprising a base having geographical outlines on its surface along opposite edges with objectives located on said outlines, the surface of the base being further provided with a plurality of variously spaced intermediate points, some of said intermediate points being idle and having danger indications adjacent thereto, and a manually manipulable member having definitely spaced points to be engaged with an objective and successively and selectively engaged with intermediate points whereby the member will be moved across the base to engage a second objective, each intermediate point being spaced from one or more adjacent 105 points a distance equal to the distance between the points on the member, the points upon the manually manipulable member being located at the under side thereof and spaced inwardly from the sides and ends of 110 the member whereby to be hidden from view when the member is viewed substantially from above. 115

In testimony whereof I affix my signature.

ELMER H. JOHNSON. [L. S.]
